Primary Examiner — Carla J Wright(74) *Attorney, Agent, or Firm* — GTC Law Group PC & Affiliates(57) **CLAIM**

The ornamental design for a case for a phone and card reader, as shown and described.

DESCRIPTION

FIG. 1 is a front elevational view of a case for a phone and card reader showing our new design;

FIG. 2 is a right-side elevational view thereof;

FIG. 3 is a rear elevational view thereof;

FIG. 4 is a top plan view thereof;

FIG. 5 is a bottom plan view thereof;

FIG. 6 is a left-side elevational view thereof;

FIG. 7 is a front, left-side, and top perspective view thereof;

FIG. 8 is a front elevational view thereof with an environmental card reader;

FIG. 9 is a right-side elevational view thereof;

FIG. 10 is a rear elevational view thereof;

FIG. 11 is a top plan view thereof;

FIG. 12 is a bottom plan view thereof;

FIG. 13 is a left-side elevational view thereof; and,

FIG. 14 is a front, left-side, and top perspective view thereof.

The broken lines throughout the drawing figures form no part of the claimed design and depict an environmental card reader and portions of the case for phone and card reader that form no part of the claimed design.

1 Claim, 4 Drawing Sheets(56)
